(No Model.)

W. P. SCOFIELD.
SAW MILL SET WORKS.

No. 289,572.

Patented Dec. 4, 1883.

UNITED STATES PATENT OFFICE.

WALTER P. SCOFIELD, OF HAWTHORN, FLORIDA.

SAW-MILL SET-WORKS.

SPECIFICATION forming part of Letters Patent No. 289,572, dated December 4, 1883.

Application filed March 8, 1883. (No model.)

To all whom it may concern:

Be it known that I, WALTER P. SCOFIELD, of Hawthorn, in the county of Alachua and State of Florida, have invented new and useful Improvements in Saw-Mills, of which the following is a full, clear, and exact description.

My invention relates to saw-mills in which the set-works of the head-blocks are driven by contact of revolving pulleys or wheels with the opposite surfaces of a wheel or drum on the pinion-carrying shaft of the carriage for automatically moving the head-blocks forward or backward for setting the log to the saw, the object of this invention being to improve the construction of the saw-mill patented to me December 12, 1882, and numbered 269,123, in such manner as shall promote the more easy and effective working of the mill and increase its durability.

The present improvements consist in a contrivance of belt-shifting devices whereby a trip-block on the log-carriage will automatically shift the belt from the loose to the tight pulley of the feed-works driving-shaft to rotate the latter only when the log-setting apparatus is to be operated; in an arrangement of pivoted bearings for such driving-shaft to support it steadily its whole length, said bearings to be swung down by a trip-plate of the carriage which passes beneath the set-works driving-pulley; and in a locking device for the connecting-rods of the oppositely-acting friction-wheels of the setting apparatus to lock said wheels out of contact with the set-works drive-wheel, all as hereinafter fully described.

Reference is to be had to the accompanying drawings, forming part of this specification, in which similar letters of reference indicate corresponding parts in all the figures.

Figure 1 is a plan view of a saw-mill fitted with my improvements, with the head-block knees removed. Fig. 2 is a side elevation of the same at the back. Fig. 3 is a cross-sectional elevation on line xx , Fig. 1, with the knees in place. Fig. 4 is an enlarged view of the lever-lock of the friction-pulleys. Fig. 5 is a detail of one of the friction-pulleys.

The track a , carriage b , with its shaft c , carrying the friction-drum or drive-wheel d , and pinions e , which pinions gear with the racks

e' of the head-block knees f , for setting the log on the carriage by the engagement with the drum or wheel d of the swinging friction-pulleys or wheels g , driven by belts from the main driving-pulley h , splined or feathered to the set-works driving-shaft i , and carried along with the carriage by the engagement of a forked arm, j , of the carriage with the grooved hub k , are all substantially similar in construction and operation to the corresponding mechanisms shown in my aforesaid patent, No. 269,123, and therefore need no extended description here. In the former arrangement the shaft i was rotated continuously as the carriage moved forward and back while the log was being sawed, which, in view of the short time required to set the log by the action of the set-works, resulted in excessive and unnecessary wear of the parts and a considerable loss of power; and to obviate these difficulties, by causing a rotation of the shaft i only when the log is to be set on the head-blocks, and to accomplish this automatically by the movement of the carriage, I have arranged on the shaft i a tight pulley, l , and a loose pulley, m , with a belt, n , which passes through the eye or fork of a shipping-lever, o , that is pivoted to a suitable support, and connects by a rod or link, p , with the short arm q of a lever, q , pivoted at r to the track a or other support, so that the weighted long arm of the lever may fall to a stop or rest, s , for normally holding the belt-shipper o upon the loose pulley m , to permit shaft i to remain at rest during the traverse of the carriage to take the log to and from the saw; and to provide for automatically starting the set-works when the carriage is gigged back after making a cut I fix to the carriage the trip block or plate t , which rides upon the short arm of lever q , or a friction-roller, o' , thereon, to raise the weighted end of the lever and ship the belt n to the tight pulley l , to rotate shaft i and make the set-works operative to turn the wheel d either way for shifting the knees of the head-blocks, which being done, by working the lever u as required to set the log, the carriage may again be started forward for making a new cut, and when the tripper t has passed by or over the short arm of lever q , the latter will lodge on stop s and again carry belt n to the loose pul-

ley *m*, permitting the shaft *i* to stop; and, if desired, one or more foot-treadles may be arranged independently of the automatic belt-shipping devices for shifting the belt to the 5 tight pulley when the carriage is forward, so that by operating the lever *u* at various points of the carriage's travel the knees *f* may be shifted as required for re-sawing, &c.

The improvements in intermediate bearings 10 for the shaft *i* consist of the swing-arms *v*, pivoted at *w* in fixed bearings *y*, arranged along the track *a* at intervals as may be required to steady and support shafts *i*, of varying length, such shafts for long mills being insufficiently supported by bearings *i'* at the ends 15 only, which permit the shafts to sag centrally and wabble, and thereby overstrain their bearings and all connected parts of the mill. The upper ends of the bearing-arms *v* are forked 20 to inclose the lower half of the shaft *i* for its support, and their lower ends are weighted, as at *z*, to cause them to swing back to a normal vertical position when they are swung over on their pivots by a cam or trip plate, *a'*, fixed to 25 the carriage, which plate *a'* I prefer to make in a curved form, extending beneath the pulley *h* and hub *k*, and connecting the arms *b'*, which are fixed to carriage *b*, and which also form movable bearings or supports *c'* for the 30 shaft *i* at both sides of the drive-pulley and hub *h k*, insuring increased steadiness of operation of the set-works. The trip-plate *a'* is rounded at both ends to swing the shaft-bearings *v* easily as the carriage moves in either 35 direction, the said bearings resuming their vertical position to support shaft *i* when the parts *h k* have passed them, as will be understood from Figs. 2 and 3; and I propose to line the shaft-bearings *c'* and *v* with Babbitt 40 or other suitable anti-friction metal, and arranged to take up the wear. The shaft *i* is thus supported amply along its length, permitting the shaft to be made of lighter material. I also propose to lock the lever *u*, to which the 45 connecting-rods *d'* of the friction-wheels *g g* are attached, by a spring-bolt, *f'*, sliding on the lever, so as to engage a slot, *g'*, of the standard *h'*, to which the lever *u* is pivoted at *j*, the bolt *f'* connecting with a pivoted hand- 50 grasp plate, *k'*, arranged at the handle end of the lever conveniently for being pressed toward the lever against the tension of a spring to withdraw the bolt and permit the lever to be worked to bring either of the friction-wheels *g* into contact with the drum *d* of the 55 set-works, as desired, and upon again permitting the bolt *f'* to enter slot *g'*, both the wheels *g* will be locked clear of the drum *d*, to avoid accidental shifting of the set-works while making a cut, or when it is not desired to shift the 60 position of the knees *f*. To prevent lost motion in the connections between the rods *d'* and their yoke-connections to the friction-wheels *g*, I thread the lower end of the yoke-arms and 65 secure the arms to the wheel-bearings by nuts *l* on the ends of the rods, as in Fig. 5, which afford a rigid connection and facilities for

taking up any wear of the joints, and I provide suitable scale-arms, *m'*, along which the pointers *n'* of the knees may indicate the set 70 of the log to the sawyer.

With the improvements above described it is believed that the mill will work more steadily and effectively at a considerable saving in power and with less attention to the 75 working parts by the sawyer, who may thus be enabled to produce more lumber or timber by the mill in a given time and at less expense.

Having thus described my invention, I claim as new and desire to secure by Letters Patent— 80

1. The combination, with the set-works drive-shaft *i* and the carriage, of tight and loose pulleys *l m* on shaft *i*, and belt-shipper *o*, connecting-rod *p*, and weighted lever *q*, substantially as shown and described. 85

2. In saw-mill set-works, the combination, with the drive-shaft *i*, provided with the tight and loose pulleys *l m*, the belt-shipper *o*, connecting-rod *p*, and weighted lever *q*, provided with the friction-roller *o'*, of the trip-plate *t* 90 on the saw-mill carriage, substantially as herein shown and described.

3. In saw-mill set-works, the combination, with the drive-shaft *i*, of intermediate bearings pivoted to fixed bearings arranged along 95 the track, and means for swinging said bearings on their pivots, substantially as herein shown and described.

4. In saw-mill set-works, the combination, with the drive-shaft *i*, of the weighted bearing-arms *v*, pivoted to fixed bearings arranged 100 along the track, and the trip-plate *a'*, secured to projections on the carriage, substantially as herein shown and described.

5. In saw-mill set-works, the combination, 105 with the drive-shaft *i* and the bearing-arms *v*, pivoted to bearings along the track, of the projections *b'*, secured to the carriage and having bearings *c'*, and the downwardly-projecting trip-plate *a'*, connecting said bearings 110 and having rounded ends, substantially as herein shown and described.

6. In saw-mill set-works, the combination, with the carriage *b*, the set-shaft *c*, provided with the drum *d*, the friction-pulley *q*, and the 115 forked arm *j*, of the drive-shaft *i*, the sliding pulley and hub *h k* on said drive-shaft, and the projections *b'*, secured to the carriage and having bearings *c'* at their ends for the drive-shaft, substantially as herein shown and de- 120 scribed.

7. In saw-mill set-works, the combination, with the set-shaft *c*, provided with the drum *d*, and the standard *h'*, provided with the notch *g'*, of the lever *u*, pivoted to said standard, the 125 spring-pressed bolt *f'* on the side of the lever, and the rods *d'*, connecting said lever and friction-wheels, substantially as herein shown and described.

WALTER P. SCOFIELD.
